(57) **CLAIM**

The ornamental design for a razor tray, as shown and described.

DESCRIPTION

FIG. 1 is a top perspective view of the razor tray showing the new design;

FIG. 2 is a top view of the razor tray;

FIG. 3 is a bottom view of the razor tray;

FIG. 4 is a side view of the razor tray;

FIG. 5 is another side view of the razor tray;

FIG. 6 is a rear view of the razor tray; and,

FIG. 7 is a front view of the razor tray.

The broken lines showing various elements of the razor tray are included for the purpose of illustrating non-claimed subject matter and form no part of the claimed design.
